UNITED STATES PATENT OFFICE.

PORTER A. STRANGE, OF DALLAS, TEXAS, ASSIGNOR OF ONE-FOURTH TO MARTHA E. WILSON, OF DALLAS, TEXAS.

REFRIGERATING APPARATUS.

1,302,726.

Specification of Letters Patent.

Patented May 6, 1919.

Application filed November 9, 1917. Serial No. 201,006.

To all whom it may concern:

Be it known that I, PORTER A. STRANGE, citizen of the United States, residing at Dallas, in the county of Dallas and State of Texas, have invented certain new and useful Improvements in Refrigerating Apparatus, of which the following is a specification.

This invention pertains to refrigerating apparatuses and particularly to evaporators.

Devices of this class are designed to keep food cool without the use of ice, depending upon aprons or cloths kept moistened with water and exposed to air currents, whereby the interior of the receptacle is cooled by the evaporation as is well understood.

The features of my invention reside in the provision of removable evaporating or cooling panels for the purpose of cleansing, replacing or repairing, which makes for sanitation; the provision of means for assuring a saturation of the cooling panels and an even distribution of water thereover; the provision of novel means for delivering water to the door-panel and for conducting the water therefrom; and the provision of certain advantageous and convenient elements adding to the usefulness and efficiency of an apparatus constructed in accordance with the invention.

In carrying out the invention I provide a receptacle of the usual shape with removable cooling panels disposed vertically in three of its sides as well as in its door. The top which carries the water tank is removable thus giving access to the panels, but access could be had otherwise. Spreaders are provided at the top of each panel and guide the water to the panel and spread it thereover. The other details will be herein-after set forth.

The invention will be more readily understood from a perusal of the following specification by reference to the accompanying drawings, in which an example of the invention is illustrated and wherein:

Figure 1 is a front elevation of an apparatus constructed in accordance with the invention, portions of the same being illustrated as broken away to show underlying structure,

Fig. 2 is a transverse vertical sectional view on the line 2—2 of Fig. 1,

Fig. 3 is a horizontal cross-sectional view,

Fig. 4 is a detail of one of the evaporating panels,

Fig. 5 is a sectional view showing the spreader construction, and

Fig. 6 is a sectional detail of the water-drain for the door.

In the drawings the numeral 1 designates an outer shell or housing and 2 an inner shell or lining spaced therefrom. The housing has a bottom 3 with a drain outlet 4 and the lining terminates short of this bottom. The housing is supported by four legs 5 secured to the corners. Each end and the back of the housing has a rectangular opening 6 of substantial size and covered with hardware cloth or equivalent material 7. These openings do not extend through the lining. Each opening has at each side an upright member 8 bent at right angles to the housing and secured to the lining whereby the latter is supported.

Each member 8 has a vertical groove or slide-way 9 in juxtaposition to the outer face of the lining. Evaporating or cooling panels 10 are inserted in the grooves from the top and slid down to the bottom 3 on which they rest. Each panel is formed of a rectangular frame 12 covered with a suitable fabric. The panels are exposed by the openings 6, but are protected by the covering 7.

The upper edges of the housing and lining are substantially flush and the panels are preferably of such length as to terminate flush therewith. A removable top section 13 is mounted on the housing and is provided with a depending flange or apron 14 surrounding the housing. The top section also has a marginal bead 15. A tank or reservoir 16 is provided on the said section and has a cover 17 which may be removed for filling. A plurality of small faucets 18 project from the lower portion of the tank and each registers with an opening 19 in the marginal portion of the top section.

The tank is filled with water and the faucets are regulated so that the water drips therefrom as the conditions may require. As will be seen the top section being removable some play must be allowed and thus it would be difficult to place the panels so that the water would always drop upon the same at the most desirable point. To overcome this spreader plates 20 are mounted in the flange

14 and are supported on downwardly inclined lips 21 bent from the upper ends of the housing toward the panels. These plates have handles 22 extending through the flange 5 so that they may be pressed against the fabric of the panels or pulled away when the top section is to be removed. The plates are disposed under the openings 19 and guide the water to the panels.

10 A slight modification is employed in the door which however has an opening 23 covered with hardware cloth 24 and a lining sheet 25. At each side of the opening upright members 26 are provided with grooves 15 27 like the members 8 and receive a panel 28 inserted from the top edge of the door. In the space between the housing and lining over the center of the door a funnel 29 is fixed so that the water dripping therefrom 20 will strike upon the upper edge of the panel 28 when the door is closed. A hole 30 in the top section registers with the funnel and a faucet 31 is mounted over said hole. The housing at the bottom of the door is 25 notched out as shown in Figs. 1 and 6 so as to receive a short spout 32 depending from the door. The water from the panel 28 is carried off by the spout and drips therefrom onto a deflector 33 which diverts 30 it into the bottom of the apparatus.

A false bottom 34 is supported by the lining above the lower end thereof and under the false bottom a water receptacle is formed. It will be seen that the panels 10 35 will not only receive water from the fountains 18 but as they rest on the bottom 3 will be kept saturated by capillary attraction. The cooling action of the apparatus is too well understood to need further explanation.

40 It will be seen that an even distribution of the water to the panels 10 is had and all the panels may be removed when desired for cleaning or other purposes. The whole apparatus makes for sanitation as the top section may be removed and cleaned and the interior cleaned and "sunned" if desired. The water from the bottom receptacle can be drained when necessary and by removing 45

the false bottom 34 the parts thereunder may be washed.

50 The foregoing description and illustration clearly express the invention, but it is to be understood that said illustration is merely an exemplification and the invention may be carried out in various other ways.

55

What I claim, is:

1. In a refrigerating apparatus, the combination with an outer housing having air admitting openings, and a lining within the housing spaced therefrom, of a removable top mounted on the housing and carrying a water tank, evaporating panels in the space between the housing and the lining and adjustable deflecting devices for guiding the water from the tank to the panels 60 and spreading the same over said panels.

2. In a refrigerating apparatus, the combination of an outer housing having air admitting openings covered with a foraminous material and open at its upper end, a lining within the housing spaced therefrom and having closed and continuous portions opposite the air admitting openings of the housing, evaporating panels disposed in the spaces between the housing and the lining 75 and removable through the open top of the housing, a top member removably mounted on the housing, a water tank mounted on the top member having means for supplying water to the panels, and a door mounted on the housing having an exposed evaporating panel receiving water from the tank.

3. In a refrigerating apparatus, the combination with an outer housing having openings, and a lining within the housing and spaced therefrom, of removable evaporating panels comprising marginal frames supporting a sheet of fabric, guides at each side of the openings receiving the panels, a door having a panel exposing opening, an evaporating panel carried by the door, means for supplying water to the door panel when the door is closed, and means for conveying the water from the door.

80 In testimony whereof I affix my signature. 95
PORTER A. STRANGE.
